UNITED STATES PATENT OFFICE.

CLAUD R. BROWN AND JESSE F. THOMAS, OF NEW LONDON, WISCONSIN.

ENGINE PISTON.

Application filed February 6, 1923. Serial No. 617,322.

To all whom it may concern:

Be it known that we, CLAUD R. BROWN and JESSE F. THOMAS, citizens of the United States, residing at New London, in the county of Waupaca and State of Wisconsin, have invented certain new and useful Improvements in Engine Pistons; and we do hereby declare the following to be a full, clear, and exact description of the invention, such as will enable others skilled in the art to which it appertains to make and use the same.

This invention relates to a piston of the type particularly adapted for use in the cylinders of internal combustion engines.

It is aimed to provide an inexpensive, self-adjusting and non-rattling piston to uniformly, expansively and intimately bear against cylinder wall throughout the length and circumference of the skirt of the piston.

A second object is to provide a novel piston with which the foregoing objects and advantages are attained being supplied to the mechanic in semi-finished condition to enable machining by him.

Another object is to provide a construction of piston having a skirt whose outer surface normally extends outwardly beyond the packing-carrying portion, or in other words is of greater exterior diameter than the packing-carrying portion, which skirt has a circumferential slit, a longitudinal slit extending therefrom toward and terminating short of the free end of the skirt, in combination with a slit substantially parallel to the latter slit and terminating short of the circumferential slit.

Another object is to provide a piston having a skirt of the construction mentioned which is provided with an interior tensioning rib or flange, which may be cast integral with the skirt.

Various additional objects and advantages will become apparent from a consideration of the description following taken in connection with accompanying drawings illustrating an operative embodiment thereof.

In said drawings:—

Figure 1 is a view in vertical central section showing the piston in place in a cylinder of an internal combustion engine;

Figure 2 is a side elevation of the piston alone;

Figure 3 is an inverted plan view of the piston alone;

Figure 4 is a cross sectional view through the piston on the line 4—4 of Figure 2 passing through the circumferential slot and transversely of the piston;

Figure 5 is a cross sectional view on the line 5—5 of Figure 2 passing transversely of the piston and through the longitudinal slots thereof and

Figure 6 is a side elevation of the piston in semi-finished condition.

Like reference characters designate like or similar parts in the different views.

The piston is generally designated 10 and in Figure 1 is shown as in use within a conventional cylinder 11 of an internal combustion engine. It is to be understood that the invention is not limited to such use but may be employed generally as a piston.

While not essential, piston 10 is preferably of any suitable metal and cast in a single piece. It has a closed head 12 as usual and that portion of the cylindrical wall adjacent to the same as at 13 is grooved at the packing-carrying portion as at 14 in order to receive rings or packings 15 which bears expansively against the inner wall of the cylinder 11. The skirt 16 is a continuation of the wall 13 and therethrough openings 17 at diametrically opposite points are provided in order to accommodate wrist pins which connect piston rods to the pistons in order to actuate them.

The skirt 16 is normally of greater external diameter than the portion 13 and the skirt 16 is exteriorly reduced if desired, as at 18, around the openings 17. Such openings 17 may be provided through bosses 19 integral with and extending inwardly from the skirt.

At one or more points, preferably two, and each midway of the lines of the openings 17 are circumferential slots or slits 20. Communicating with slots 20 are slots 21 which extend longitudinally of the skirt 16 and terminate short of the free end thereof.

Parallel with the slits or slots 21 and relatively close thereto are slots or slits 22 which extend inwardly from the free end of skirt 16 and terminate short of the slit 20. Slots 21 and 22 are preferably angularly disposed to a slight extent as shown.

We have particularly shown in Figure 2, the skirt 16 as normally expanded. When the piston is disposed within the cylinder 11, the skirt 16 will be contracted, as it is of metal and resilient to a certain de-

gree. The slits 20, 21 and 22 enabling the skirt to be self-adjusting or self-adapting with respect to the inner surface of the cylinder, thus always uniformly and intimately contacting with such wall.

A rib or flange 23 may be cast integral with the skirt to extend interiorly thereof directly below the bosses 19 and if desired, connected therewith as shown. The slits 10 21 and 22 extend through the flange 23. Such flange serves to tension the skirt 16, particularly when the latter is compressed and in place as in Figure 1.

Referring to Figure 6, the piston is shown 15 in a semi-finished condition or state. It differs from the preceding views in that slits 21 do not extend completely to slit 20 as a fin 21^a, and in that slits 22 are not open at the lower end of the skirt 16 20 as a fin 22^a is provided in each slit 22. The piston may be sold in this condition. Said fins 21^a and 22^a will prevent such flexure or yielding of the piston as will interfere with machining thereof, as when it is reduced in diameter to fit a particular cylinder. Before the piston is operatively placed in a cylinder, fins 21^a and 22^a are removed as by means of a hack saw.

Various changes in the details of construction 30 may be resorted to provided they fall within the spirit and scope of the invention.

We claim as our invention:—

1. A piston having a skirt provided with 35 a circumferential slit, and other slits parallel to one another on lines cutting said circumferential slit intermediate of its ends, one of the last mentioned slits intersecting said circumferential slit, and the other slits 40 intersecting the edge of the skirt.

2. A piston having a skirt provided with a circumferential slit, said skirt having a slit extending therefrom and terminating short of the free end of the skirt, and said skirt having a slit substantially parallel 45 with the last slit extending inwardly from its free end wall and terminating short of the circumferential slit, and each of the second and third mentioned slits being substantially equidistant from their respective 50 adjacent ends of the first slit.

3. A piston having a skirt provided with a circumferential slit, said skirt having a slit extending therefrom and terminating short of the free end of the skirt, and said 55 skirt having a slit substantially parallel with the last slit extending inwardly from its free end wall and terminating short of the circumferential slit and each of the second and third mentioned slits being substantially equidistant from their respective 60 adjacent ends of the first slit, said skirt being of greater external diameter than the remainder of the piston so that it will be self-fitting, said skirt having pin receiving 65 openings therethrough, the skirt being exteriorly reduced about said openings, bosses about said openings and integral with the piston, and a tensioning flange integral with and within the piston crossing the second and third mentioned slits and merging 70 into the metal of the skirt and bosses.

In testimony whereof we affix our signatures in presence of two witnesses.

CLAUD R. BROWN.
JESSE F. THOMAS.
